PORTABLE INCANDESCENT LAMP

Martin Gindoff, Plainview, N.Y., assignor to Tensor Corporation, a corporation of New York

Filed Sept. 6, 1963, Ser. No. 76,505

Term of patent 14 years

(Cl. D48—20)

FIG. 1 is a side elevational view of a portable incandescent lamp showing my new design; the opposite side thereof is a mirror image as seen from FIGS. 2 and 3; FIG. 2 is a top plan view thereof;

FIG. 3 is a left side elevational view with respect to FIG. 1 and illustrates the front of said lamp; and

FIG. 4 is a fragmentary sectional view taken along line 4-4 of FIG. 3.

The dominant features of the design reside in the portions shown in full lines in the figures.

I claim:

The ornamental design for a portable incandescent lamp, as shown and described.
